UNITED STATES PATENT OFFICE.

ARTHUR W. SMITH, OF NEW YORK, N. Y., ASSIGNOR, BY MESNE ASSIGNMENTS, TO REMINGTON TYPEWRITER COMPANY, OF ILION, NEW YORK, A CORPORATION OF NEW YORK.

TYPE-WRITING MACHINE.

1,210,009.

Specification of Letters Patent. Patented Dec. 26, 1916.

Application filed October 10, 1912. Serial No. 724,914.

To all whom it may concern:

Be it known that I, ARTHUR W. SMITH, citizen of the United States, and resident of the borough of Manhattan, city of New York, in the county of New York and State of New York, have invented certain new and useful Improvements in Type-Writing Machines, of which the following is a specification.

10 My invention relates especially to mechanism for differentially feeding work sheets in typewriting machines and for producing a plurality of inked or original typewritten copies and the general object of said invention is to provide improved mechanism of the character specified.

20 To the above and other ends my invention consists in the features of construction, combinations of devices and arrangements of parts hereinafter described and particularly pointed out in the claims.

25 The embodiment of my invention herein disclosed was particularly designed for way-billing purposes but it will be understood that the principles of said invention may be employed for producing other kinds of typewritten work besides way-bills; also it is to be understood that while I have herein shown my invention as embodied in a Smith 30 Premier No. 10 typewriting machine, said invention may be applied in whole or in part to other styles of typewriting machines.

35 In express company way-billing of the character for which the present form of my invention is especially adapted, it is desirable to produce two copies of each way-bill, one of which is used as a label being pasted on the parcel or package, and the other being a way-bill proper; also an abstract of certain entries on each way-bill for the auditing department, and a complete record of each bill for the home office; that is to say, three first or original typewritten 45 copies of the complete series of entries on each bill are needed and in addition a fourth or record copy containing in condensed form abstracts or certain entries only of each bill. Thus ribbon mechanism is necessary for producing four first copies and also mechanism is needed for feeding three work sheets together and for so controlling the fourth sheet that it is fed differentially or inter-

mittently and is only written upon at pre-determined intervals.

55 In carrying out the invention the work sheets which are preferably continuous are wound on a set of roll carriers which are supported on a support or truck slidably mounted in the rear of the machine and 60 connected to move or slide back and forth with the platen carriage thereof. The platen carriage supports a divided rotary platen composed of two coaxial sections arranged end to end, the left-hand section being associated with paper feeding devices and being employed exclusively as a device or means for feeding or advancing the work sheets over the right-hand platen section 65 with which coöperates the usual printing instruments. Line spacing devices are associated with the left-hand platen section and turn the same at each actuation, said section being connected with the right-hand platen section by devices including disconnectible 70 pawl and ratchet mechanism in such a way as to cause the right-hand section to be given a rotary movement at desired predetermined intervals, such rotary movement being in a direction opposite from the line spacing or 75 paper-advancing movement of the left-hand platen section. Concurrently with this backward movement a turning movement is also communicated to a receiving roll carrier for the record sheet aforesaid, said carrier 80 being mounted on the carriage. This record sheet is the innermost sheet of the set of four superposed or overlying work sheets and is narrow so that it does not overlie the left-hand platen section and consequently 85 does not coöperate with the paper feeding devices associated therewith. The three other work sheets which are so wide as to extend over substantially the full length of the two platen sections are superposed 90 upon the narrow record work sheet. The forward or outside sheets are interleaved with the plies or sections of a special or auxiliary ribbon which is mounted on a platen carriage and is connected to be 95 fed or advanced when the right-hand platen section is turned. The narrow record sheet passes through an opening or slot between the right-hand platen section and a type shield extending the full length of said section and connected therewith. This shield is 100 105

normally in the path of the printing types so that it prevents such types from making impressions on the record sheet. However, when the intermittent backward movement 5 of the right-hand platen section takes place a corresponding backward or downward movement of the type shield occurs, carrying said shield out of the path of the printing types and so that when they are actuated 10 their impressions may be made not only on the outermost sheets as theretofore but also on the fourth or narrow record sheet. The parts are arranged so that the shield remains in inoperative position long enough 15 to permit the writing of one line on the record sheet, said shield being automatically restored to the position in the path of the types at the next actuation of the line spacing mechanism. The outermost sheets 20 may be severed or torn off in sections when completed as desired, this taking place usually as each way-bill is finished, a severing device being provided for the purpose. The record sheet need be removed from the receiving holder only at long intervals and as may be convenient.

My invention will be described and explained in detail in connection with the accompanying drawings, wherein—

30 Figure 1 is a fragmentary end view partly in section of the upper part of a front-strike Smith Premier typewriting machine embodying my invention. Figs. 2 and 3 are fragmentary front elevations 35 showing respectively the right-hand and left-hand end portions of the platen and associate parts. Figs. 4 and 5 are vertical sectional views taken centrally through the platen and showing respectively the right-hand and left-hand end portions thereof together with associate parts. Fig. 6 is a fragmentary diagrammatic plan view showing the ribbon spools and guiding devices and illustrating the course of the ribbon in 45 passing from one spool to the other. Fig. 7 is a sectional view taken transversely of the platen on planes indicated by the broken dotted line $x-x$ in Fig. 4 and looking in the direction of the arrows at said line. 50 Figs. 8 and 9 are perspective views of details of construction, Fig. 8 showing a relatively fixed cam for disconnecting the pawl and ratchet mechanism and the mounting of said cam, and Fig. 9 showing detent devices 55 associated with the receiving carrier for the record sheet. Fig. 10 is an end view of the pawl and ratchet mechanism comprised in the connection between the left-hand and right-hand platen sections, side 60 view showing also the cam for disconnecting the pawl and ratchet. Fig. 11 is a diagrammatic view transverse of the platen and showing the interleaving of the work sheets and the plies of ribbon. Figs. 12 and 13 are respectively fragmentary face

views of the way-bill proper and of the innermost or record sheet. Fig. 14 is a fragmentary end elevation showing the typewriting machine and the slideable truck or support for the rolls of paper or work sheets. Fig. 15 shows a rear elevation of said truck.

As appears from Figs. 1 and 14 the main frame of the machine comprises end plates 1 and a connecting top plate 2 from which 75 rise standards 3 supporting an inclined grooved track-way 4 which co-operates through anti-friction rollers 5 with the rear or slide bar 6 of a carriage truck, this truck further including end plates 7. The truck 80 provides a support for a detachable platen frame or carrier proper which comprises end bars or plates 8 and connecting cross rods 9 and 10. Journaled in the end plates 8 is a platen, spindle or axle 11. When the 85 platen frame is in place on the truck the axle 11 bears in seats or depressions 12 in the end plate 7 of the truck which thus provides a support for the platen frame and the platen mounted thereon. As thus far described the parts are like those of the No. 10 front-strike Smith Premier machine.

The platen that is supported on the axle 11 is of novel construction and consists of two parts or sections, the details of which are best illustrated in Figs. 4 and 5. The left-hand section consists of a hollow wooden core 13 surrounding the axle 11 and extending substantially throughout the length of the divided platen and further includes a shorter sheath portion 14 surrounding the left-hand end portion of said core. Secured to the left end of the core 13 by wood screws 13^a is a platen head 15, the hub of which receives a set screw 16 that engages the axle 11 and thus maintains the left-hand platen section in rigid relationship with said axle. The right-hand end portion of the core 13 is slightly reduced and provides a bearing surface for a metal tube or sleeve 17 which serves as the core of the right-hand platen section, said section further comprising a sheath 18 of rubber or the like which is suitably secured to the tube 17 between end rings 19 and 20 which are fastened to the tube 17 by screws 21. The two sections being coaxial and of the same diameter present a substantially uninterrupted and uniform surface throughout. The right-hand platen section is loosely mounted on the left-hand platen section so that relative turning movements may take place between the two platen sections or platens. At the right-hand end of the divided platen is a line spacing ratchet wheel 22 which is provided at its outer face with a series of projections or teeth 23; and with corresponding peripheral ridges, edges or teeth 24. The hub portion 25 of this wheel 22 fits within an annulus 26 and is 130

secured in fixed relationship therewith as by a pin 27. This pin also serves to secure to the outer face of the annulus and in fixed relationship therewith and with the 5 wheel 22 a ring 28 provided with a series of peripheral gear teeth 29. The annulus 26 comprises a series of stepped faces and its inner end portion fits within the right-hand end of the core 13, said annulus being 10 secured to said core by screws 30, thus fixing the relationship between the left-hand platen section and the line spacing wheel 22 and gear teeth 29.

The line spacing wheel is provided with 15 a fewer number of line spacing teeth 23 than is common, twelve of such teeth being shown in the present instance. Coöperative with these teeth are line spacing devices of the usual construction comprising a spring 20 pressed plunger 31 (Fig. 1) terminating in a beveled tooth for coöperation with the teeth 23. Said plunger is seated in a barrel-like bearing 32 that is mounted in an opening 33 in the right-hand end plate 7. A 25 rock shaft 34 bears in said end plate and is operatively connected to the barrel 32, said rock shaft terminating at the front in a downwardly extending finger piece or line spacing handle 34^a which when actuated 30 causes the plunger or pawl member 31, coöperating with the teeth 23, to turn the left-hand platen section through a line spacing distance. A restoring spring 35 is connected with the barrel 32 in the usual way. It 35 will be observed that between the peripheral ridges or teeth 24 are curved depressions 36. Coöperative with these depressions is a detent wheel 37 pivoted on a spring arm 38 secured by a screw 39 to the right-hand end 40 plate 8 of the platen frame. The detent 37 fits accurately in and coöperates with the depressions 36 to maintain the left-hand platen section in predetermined line spacing positions and to determine finally the extent of 45 the line spacing movements.

Pivotaly supported on the frame rod 10 and coöperative with the left-hand platen section is a paper guide plate 40 (Fig. 3) of ordinary construction, said plate providing 50 a mounting for front pressure rolls 41 and rear pressure rolls 42, the two sets of rolls coöperating with the left-hand platen section only and assisting to advance or line space the paper when the line spacing devices are actuated. No paper feeding devices coöperate directly with the right-hand platen section, the main sheets being advanced over this section while it is motionless, by the coöperation between the feed 55 rollers and the left-hand platen section.

Connected to the right-hand platen section is a shield which is in the form of a strip 43 (Figs. 1, 2 and 7) of very thin sheet metal secured at its ends by screws 44 to the 60 platen rings 19 and 20. The body of the

strip is off-set slightly forward so as to provide a narrow opening or slot-way 45 between the strip or shield and the platen face. Normally as shown in Fig. 1 the shield is in the path of the types 46 when the type bars 70 47 carrying said types swing toward the platen, so that the types will coöperate with the shield and will fail to make an impression on a sheet which may pass through the slot-way 45. The term shield is used in a 75 broad sense for means that prevent the coöperation of the types with the printing face of the platen itself. Automatic means are provided for turning the right-hand platen section backward or in reverse direction at predetermined intervals and thus swinging down the shield 43 to an inoperative position (Fig. 7) out of the path of the types and so that the types may coöperate directly with the face of the platen and imprint on the paper passing through the slot 80 45. The automatic means for thus actuating the right-hand platen section and the type shield is operated from the left-hand platen section through the gear 29 secured at the 85 right-hand end of said section. Coöperative with the gear 29 is a somewhat smaller gear 48 mounted loosely on a hub 49 (Fig. 4) of a ratchet wheel 50, the hub of said shield is operated from the left-hand platen section through the gear 29 secured at the 90 right-hand end of said section. Coöperative with the gear 29 is a somewhat smaller gear 48 mounted loosely on a hub 49 (Fig. 4) of a ratchet wheel 50, the hub of said 95 ratchet wheel being fixed by a cross pin 51 to a rock shaft 52 arranged and supported above the right-hand platen section and extending longitudinally thereof. The left-hand end of said shaft takes bearings in an arm 53 which rises from the frame rod 9 as 100 shown in Fig. 2 and is secured thereto by a cross pin 54. The right-hand end of the shaft is supported in an arm or bracket 55 which is secured by a cross pin 56 to said rod. The details of the bracket piece 55 are 105 best shown in Fig. 8. Curving forward from the upper portion of the bracket piece is an extension 57 terminating in a head 58. The inner face of this head is formed with cam devices comprising two cam edges 59, 110 a connecting circular face or dwell 60 and a circular face 61 of lesser diameter connecting the inner ends of the cam edges 59. Inward from the cam devices is a boss 62 and the entire head is formed with a central hole 63 in which the hub 49 takes a bearing as shown in Fig. 4, the rock shaft 52 being thus supported through said hub. 115 Mounted loosely on the shaft between the arm 53 and the ratchet 50 is a receiving 120 roll carrier or spool 64 secured to the right-hand end of which is a ratchet wheel 65 like the ratchet wheel 50 and contiguous to the same (Figs. 1, 2, 4, 7, 9 and 10). The left-hand end portion of the carrier 64 is 125 formed with a polygonal or hexagonal head 66 with which coöperates at diametrically opposite faces a double detent spring 67 secured to the rod 9 by a screw 68 (Fig. 9), these devices serving to hold the roll car- 130

rier in predetermined positions after it has been turned for winding the paper thereon. Fixed to the outer reduced end of the shaft 52 by set screws 69 is the hub portion 70 of 5 a crank arm 71 having its forward end offset inwardly. Said forward end carries a depending adjustable link 72 and as best shown in Fig. 7 said link is pivotally connected with the right-hand platen section 10 by a shouldered screw 73 which is secured in the ring 20. The right-hand platen section is thus connected with the shaft 52 through the link and the crank arm. The gear wheel 48 serves primarily as a pawl carrier and 15 actuator having pivotally secured to its inner face at 74 a forwardly extending pawl 75, the engaging end or tooth of said pawl being in the plane of the ratchets 50 and 65 and being broad enough to coöperate with 20 both of said ratchets. A spring 76 constantly presses said pawl toward said ratchets but the pawl is controlled by the cam, faces heretofore described through a lateral pin 77 which extends rightward 25 from the pawl 75, near its free end, through a hole 78 in the gear wheel 48 so that it may engage said cam devices. When the pin 77 rests on the circular face 60 as shown in Fig. 10 it is held out of operation; but when 30 the pawl is in engagement with the face 61 as shown in Fig. 7 it is operative on the ratchet wheels. It will be understood that once during each rotation of the gear wheel 48 under the actuation of the left-hand 35 platen section the pawl 75 will be rotated to a point where the pin 77, sliding over the face or edge 60, will engage the rear cam edge 59 and that then the pawl spring 76 will force the pawl into engagement with 40 the coöoperative ratchet wheel so that during the next turning movement communicated to the gear wheel 48 the pawl will operate on the ratchets to turn the roll carrier 64 and to rotate the right-hand platen section 45 and the shield 43 to the position shown in Fig. 7. This figure shows the parts at the end of the movement communicated by the pawl 75, and it will be observed that the pin 77 is contiguous to the forward cam edge 50 59 so that at the next actuation of the gear wheel 48, said cam edge acting on the pin, will lift the pawl out of operation and cause the pin to engage with the dwell face 60 as shown in Fig. 10. When the ratchet wheel 55 is thus freed from the pawl the right-hand platen section and the shield 43 will be returned to the normal position of Fig. 1 by automatic means comprising a restoring spring 79 connected at its forward end to 60 a screw 80 on the right-hand platen section and at its rear end to a screw 81 on the arm 55. A stop pin or device 20^a on the ring 20 coöperates with the cross rod 9 as shown in Fig. 1 to limit the return movement of 65 the right-hand platen section. The stop pin

20^a moves away from the stop device or rod 9 to the position shown in Fig. 7 when the platen section and shield 43 are turned to abnormal position. It will be observed that the spring 79 constitutes means tending constantly to turn the right-hand platen or platen section in one direction, while means are provided comprising the line spacing handle 34^a which acts through the left-hand platen section to overcome the spring 79 and turns the right-hand platen in the opposite direction. It will be understood that while the right-hand platen section is thus turned against the spring 79 once during each complete rotation of the gear wheel 48, 80 the number of such turning movements may be increased or decreased as desired and in accordance with the work in hand. In the present instance it is desired to write on the record sheet once only during the filling in 85 of a way-bill and therefore only one actuating pawl 75 is employed, or from another point of view, only one cam is provided to coöperate with the single pawl.

As heretofore stated the work sheets, four 90 sheets of which are shown and numbered 82, 83, 84 and 85, are preferably in roll form as shown in Figs. 14 and 15 and are supported independently of the platen carriage by means which *per se* are not my invention. 95 The rolls of paper are arranged one above the other and are supported on rotary spindles or carriers 86 which are mounted on an upright rectangular frame 87, said frame being secured to a movable truck 88 which 100 is connected by ball bearings 89 with a fixed track-way 90. Said track-way in turn is secured to brackets 91 which rise from a shelf 92 fixed at the rear of the table or support 93 on which the typewriting machine 105 rests. Horizontally disposed arms 94 pivotally connect the frame 87 to the platen carriage and cause the traveling roll support comprising the frame 87 and truck 88 to travel back and forth with the carriage. 110 The construction is such that the weight of the rolled work sheets and their supporting devices is taken off the carriage, thus 115 conducting to a lighter and easier running thereof. The work sheets are led or drawn upward from the rear with their respective rolls and over guide rods 95 and 96 on the traveling frame 87 and thence forward over the usual paper table 97 and around the platen. The three outer sheets 82, 83 and 84 120 are substantially of the full width of the platen and at their right-hand end portions are in the control of the paper feeding devices 41 and 42; while the innermost sheet 85, which is the narrow record sheet, passes 125 around the right-hand platen section only so that it is not controlled by said paper feeding devices. Said record sheet 85 is led around the platen and upward under and to the rear of the roll receiving carrier 64, 130

its free end being secured to said carrier by suitable devices. As herein shown in Fig. 4, said devices may comprise a longitudinal groove 98 in the body of the carrier and a 5 coöperating pivoted clamping bar 99 for forcing the paper into the groove and clamping it to the carrier.

Figs. 12 and 13 show respectively fragmentary portions of the way-bill proper, 10 which may be the sheet 83, and the record sheet 85. The way-bill comprises a series of printed blanks as shown, one blank following another and being separated by perforations 100 to facilitate tearing off from the 15 roll after being filled in or printed. The right-hand portion of the bill to the right of the dividing line 101 is filled in on the typewriting machine while the left-hand portion is divided into spaces which are to 20 be stamped at transfer offices. It will be observed that the right-hand portion of the bill comprises a series of lines to be filled in, seven of such lines being shown in the present instance, although the number may be 25 varied. These lines are preferably a line space distance apart so that after filling in the blanks in one line an actuation of the line spacing handle 34^a will advance the next line to position to be filled in. All of 30 the data in each of the lines is written on the three outer sheets 82, 83 and 84, although since one of these sheets is to be used for a label and the other for an office copy they need not necessarily be printed in blank as 35 at the left of the dividing line 101 but only need bear the printing at the right of said line. The inner sheet 85 which is to go to the auditor's office only requires the data on the first line of each way-bill to be reproduced; that is, the "No." the "Date," the "Town or City," the "Express Charges" 40 and "To Whom Paid."

Preferably each of the four work sheets is printed directly from an inking ribbon so 45 as to obtain a first copy and to this end special inking mechanism is provided, mounted on the platen frame or carrier. Referring especially to Figs. 2, 3, 5 and 6 it will be seen that said mechanism comprises a 50 pair of ribbon spools 102 arranged side by side at the left-hand side of the platen and co-axially therewith. The platen axle 11 extends beyond the left-hand end plate 7 and has fitting over it and secured to it by 55 a screw 103 an extension 104 on which the spools 102 are loosely mounted, each spool bearing on a reduced portion 105 of said extension and being confined between the shoulder formed by said reduced portion at 60 one end and a disk 106 secured to the opposite face thereof. Beyond the left-hand spool the extension 104 is further reduced at 107 and fixed on this reduced portion is a finger wheel 108 of the usual style, a corresponding finger wheel being secured at the

opposite end of the axle 11. The spools 102 are spaced some distance apart and in the space between them is arranged a connecting member or lever 109, this lever being pivoted at 110 in a slot or kerf 111 in the extension 104.

One end of the lever 109 is provided with oppositely disposed teeth 112 which are adapted for alternate coöperation with sets of circularly arranged teeth or projections 75 113 struck from the inner flanges of the spools 102. The opposite end of the lever 109 is provided with a friction spring 114 which is engageable with the opposite faces of the inner flanges of the spools 102. A detent spring 115 coöperates with the lever 109 to maintain it in engagement with one or the other set of teeth 113. When engaged with a tooth of one set the member 109 connects the associate spool with the axle 11 so 80 that said spool will turn with said axle and with the left-hand platen section so as to wind the ribbon on said spool. Simultaneously the ribbon is unwound from the other spool which is at this time loose on the extension 104 but is prevented from turning too freely by the engagement of the friction spring 114 with its inner surface. Secured to the left-hand end bar 8 of the platen frame by a screw 116 is a guide 95 bracket 117 which is off-set forward and extends leftward transversely of the spools, being provided with an integral arm 118 which bears on the axle 11 and assists to maintain the bracket in proper position on 100 the platen frame. Said bracket is provided on its outer face opposite the spools 102 with diagonal turning bars 119. The right-hand end portion of the bracket is provided with four vertically disposed and parallel guiding devices or bars numbered respectively 120, 120^a, 120^b and 120^c, these guiding devices projecting different extents from the face of the guide 117. At the opposite end 105 of the platen there is secured to the end bar 8 a forwardly extending arm 121 which supports a guiding device comprising two parallel upright arms or bars 122. The ribbon 123 is led off from the left-hand spool and under the bracket 117, thence over the associate turning bar 119 and inward along the front or printing face of the platen, passing through and under the adjacent turning bar 119 as well as under all of the vertical guiding devices or bars. At the right-hand end 115 of the platen the ribbon passes around the rearmost arm 122 and thence is reversed, being directed back toward the left along the platen, then around the guiding device 120^c and rightward again along the platen, then around the forward of the two upright arms 122 and leftward again along the platen, passing under the guiding device 120^b and over the guiding device 120, thence around 120 the right-hand turning bar 119 by which the 130

course of the ribbon is directed at right angles to its former course and passing around and under the bracket 117 is directed to the other or right-hand spool 102. It will be seen that by this arrangement four parallel thicknesses or plies of transfer media or ink ribbon are provided extending along the front or printing face of the platen. Preferably the front ply of the ribbon is threaded through the usual ribbon vibrator 124, said vibrator, shown in Figs. 1 and 2 being pivotally supported on an arm 125 fixed to a rock shaft 126 which is pivoted to the upper part of the machine frame and is operative from the printing keys by connections comprising a crank arm 127 extending rearward from the rock shaft 126 and a downwardly extending link 128 connected to said arm 127. Normally the vibrator maintains the outer ribbon ply down below the printing point *p* as shown in Fig. 2 so that any writing which may be on the work sheet immediately underlying the outer ply, in the present instance the work sheet 82, will be exposed as soon as printed. It is to be understood, of course, that the number of ribbon plies will vary with the number of work sheets printed and that, instead of the outer ply being controlled by the vibrator, said vibrator may receive the regular ribbon of the machine so that with the supplementary ribbon 123 arranged in four plies as described, five first copies may be taken. However, the arrangement illustrated is preferred for the character of work now under consideration. In Fig. 11 is diagrammatically illustrated the relationship of the four work sheets 82, 83, 84 and 85 with the interleaved plies of the ribbon 111. It will be observed that the record sheet is next to the platen and passes between it and the shield 43, said shield normally covering the printing point on the work sheet 85, the first ply of the ribbon which is intended to coöperate with the work sheet 85 being forward of the shield and contiguous thereto. The ribbon plies alternate with the work sheets and the forward ribbon ply is normally lowered below the printing point by reason of being within the control of the vibrator, as is clear from Fig. 11. The record sheet 85 winds on the receiving roll holder 64 while the three outer sheets pass above said roll holder and if not torn off will be directed rearward and may coöperate with a guide rod 129 on the frame 87. To assist in tearing off the sections of the written way-bills or work sheets, a severing device or blade 130 is arranged lengthwise of the platen above the printing line, said blade being secured by screws 131 to the end bars 8 of the platen frame. The front upper portion of the blade is preferably beveled to provide a sharp cutting edge and as illustrated in Fig. 2 this beveled portion may be provided with a scale or indicat-

ing device 132 for coöperation with the paper.

From what has been said heretofore it will not be necessary to explain the operation of the mechanism other than briefly. Assuming that the first line of one of the way-bills is opposite the printing point and that the parts are in the position illustrated in Fig. 7 with the shield 43 lowered, then each type actuation will cause an impression to be made through the ribbon plies on each of the four associate sheets so that when the various items in the first line of the way-bill have been printed as indicated at 133 by "x" marks in Fig. 12, said line will also be reproduced on each of the other wide sheets 82 and 84 and also on the narrow record sheet 85. This record sheet may, if desired, be printed in like form corresponding with the printing in the first line of the way-bill, or as shown in Fig. 13 it may be a plain sheet not containing any printed blanks. After the first line 133 has been printed, an actuation of the line spacing handle 34^a will, through the coöperation of the feed rollers 41 and 42 with the left-hand platen section, not only advance the three outer sheets but will also, through gears 29 and 48, advance the pawl 75 and cause the pin 77, acting against the forward cam edge 59, to lift the pawl out of operation, said pawl moving idly to the Fig. 10 position, thus permitting the shield 43 to return automatically to a position opposite the printing point and covering the sheet 85. Consequently during the printing of the second and subsequent lines on the three outer sheets and the line spacing of these sheets the pawl 75 will turn idly and without affecting the ratchets 50 and 65, the pin 77 sliding over the dwell or face 60. Assuming that the last line of the way-bill has been printed and that the pin will have moved to the dotted line position indicated at 77^a in Fig. 10, then at the next actuation of the line spacing handle to advance to the first line of the next succeeding way-bill, said pin will drop down, the rear cam edge 59 allowing the pawl to engage with the teeth of the ratchet wheels 50 and 65, turning said ratchets and through them the roll holder 64 and the rock shaft 52. The turning of the roll holder causes a single line spacing movement of the record sheet 85 and presents a fresh part thereof opposite the printing line; while the turning of the rock shaft 52 operates through the crank arm 71 and the connecting link to turn the right-hand platen section and lower the shield 43, so that if now the types are actuated the first line of the next bill sheet will be printed and will be reproduced not only on the three outer sheets but also on the underlying sheet 85 as indicated at 133^a (Fig. 13). The operations above outlined are repeated each

time a way-bill is printed so that for each printing of the entire set of way-bill blanks there is a single line written on the record sheet 85. It will be understood that during the entire series of line spacing operations for printing the lines making up a way-bill, the record sheet will advance but once, this advance preferably taking place during the movement of the last line of one way-bill to the first line of the next succeeding way-bill. During the other line spacing movements of the way-bill the right-hand platen section and the shield will remain motionless and the three outer work sheets will be advanced over said right-hand platen section by the paper feeding devices at the left-hand end thereof without affecting the latter. Also it will be seen that during the backward movement of the right-hand platen section as described the record sheet 84 will be moving forward and winding on the receiving carrier 64.

My present invention provides for doing away with the writing of way-bills by hand in booklets as heretofore and for greatly facilitating the speed of writing and the legibility of the work.

Various changes may be made in the invention and parts used without other parts, all without departing from said invention.

What I claim as new and desire to secure by Letters Patent, is:—

1. In a typewriting machine, the combination of a traveling carriage, a platen, a shield covering the printing point and connected with said platen, said shield being mounted to participate in the traveling movements of said carriage, and means operative to move said platen and cause said shield to uncover the printing point.

2. In a typewriting machine, the combination of a traveling carriage, a platen, a shield for covering the printing point thereon, said shield being mounted to participate in the traveling movements of said carriage, and means operating automatically to move said platen and cause said shield to uncover the printing point.

3. In a typewriting machine, the combination of a traveling carriage, a platen, printing types, a shield normally covering the printing line and receiving the impact of the types during the writing of the line, said shield being mounted to participate in the traveling movements of said carriage, and means for moving said shield to uncover the printing line on the platen.

4. In a typewriting machine, the combination of a platen, printing types, a shield normally covering the printing line and receiving the impact of the types during the writing of the line, means for moving said shield out of the path of the types, and stop devices for said shield.

5. In a typewriting machine, the combi-

nation of a platen, printing types, a shield normally covering the printing line and receiving the impact of the types during the writing of the line, means for moving said shield out of the path of the types and also back again into the path of the types, and stop devices for limiting the movement of said shield in one direction.

6. In a typewriting machine, the combination of a traveling carriage, a platen, a shield covering the printing point thereon, said shield being mounted to participate in the traveling movements of said carriage, and means operating automatically at predetermined intervals to move said shield and uncover the printing point.

7. In a typewriting machine, the combination of a traveling carriage, a platen, a shield normally covering the printing point thereon, said shield being mounted to participate in the traveling movements of said carriage, and means for automatically moving the shield to uncover the printing point.

8. In a typewriting machine, the combination of a traveling carriage, a platen, printing types co-operative therewith and a shield normally in the path of the types, said shield being mounted to participate in the traveling movements of said carriage, and means for moving the shield automatically out of the path of the types.

9. In a typewriting machine, the combination of a traveling carriage, a platen, printing types, a shield on the platen normally in the path of the types as they are actuated in the writing of a line said shield being mounted to participate in the traveling movements of said carriage, and means for moving the shield out of the path of the types.

10. In a typewriting machine, the combination of a traveling carriage, a platen, an inking ribbon, printing types, a shield normally interposed between the inking ribbon and the paper on the platen, said shield being mounted to participate in the traveling movements of said carriage, and means for moving the shield to inoperative position.

11. In a typewriting machine, the combination of a rotary platen, a bar-like shield secured thereto and providing a paper slot between itself and the platen, printing types, said shield being normally in the path of the types, and means for communicating rotary movement to the platen and moving the shield out of the path of the types.

12. In a typewriting machine, the combination of types, a platen, means for communicating a rotary movement to said platen, and a type shield mounted on said platen, said type shield being automatically moved out of and into the path of said types when said means is actuated.

13. In a typewriting machine, the combination of a platen, a shield covering the

printing point thereon, and means operating automatically to move said platen and cause said shield to uncover the printing point, said means comprising a second platen and line spacing devices therefor.

14. In a typewriting machine, the combination of types, a platen, a shield normally interposed in the path of the types, means for moving said shield out of the path of the types, and means for moving said shield back again into the path of the types.

15. In a typewriting machine, the combination of two platens, and hand actuated means for moving said platens oppositely at a single operation.

16. In a typewriting machine, the combination of two platens, and line spacing devices operative to advance one of said platens in line spacing direction and to move the other platen oppositely.

17. In a typewriting machine, the combination of two platens, and line spacing devices operative to advance one of said platens in line spacing direction, certain actuations only of said devices operating to move the other platen in the opposite direction.

18. In a typewriting machine, the combination of two rotary platens, and means operative by a single finger piece for communicating opposite rotary movements to said platens.

19. In a typewriting machine, the combination of a platen, means tending constantly to turn said platen in one direction, and automatic means for turning said platen in the opposite direction.

20. In a typewriting machine, the combination of two rotary platens, means connected with one of said platens and tending constantly to turn it in one direction, and means connected with the other of said platens for turning the first named platen in the opposite direction.

21. In a typewriting machine, the combination of two rotary platens, a spring tending constantly to turn one of said platens in one direction, stop devices for said platen, and means operative through the other platen for turning the first named platen in the opposite direction.

22. In a typewriting machine, the combination of two rotary platens, and line spacing devices for rotating one of said platens at each actuation, said devices operating intermittently to turn said other platen in the opposite direction.

23. In a typewriting machine, the combination of a rotary platen, a second rotary platen coaxial therewith, paper feeding devices co-operative with said first named platen, line spacing devices co-operative with said first named platen to advance paper therewith, and connections for enabling said line spacing devices to intermittently turn said second platen in the opposite direction.

24. In a typewriting machine, the combination of two platens, hand actuated devices for moving said platens oppositely, and automatic means for restoring one of said platens to the first position from which it was moved.

25. In a typewriting machine, the combination of two platens, line spacing devices operative to advance one of said platens in line spacing direction and to move the other platen oppositely, and means operating automatically to restore said other platen to its first position.

26. In a typewriting machine, the combination of two rotary platens, hand actuated means for communicating opposite rotary movements to said platens, and spring means for restoring one of said platens to its first or original position after it has been rotated by said hand actuated means.

27. In a typewriting machine, the combination of a rotary platen, a second rotary platen co-axial therewith, paper feeding devices co-operative with said first named platen, line spacing devices co-operative with said first named platen to advance paper over both said platens, a shield normally covering the printing point on said second platen and connected with said second platen, and connections for enabling said line spacing devices to intermittently turn said second platen and cause said shield to uncover the printing point thereon.

28. In a typewriting machine, the combination of types, two rotary platens, a shield normally covering the printing point on one of said platens, and line spacing devices for rotating the other of said platens at each actuation, said devices operating intermittently to move the shield out of the path of the types.

29. In a typewriting machine, the combination of two rotary platens, a shield normally covering the printing point on one of said platens and connected therewith, and hand actuated means for communicating opposite rotary movements to said platens and simultaneously moving said shield to uncover the printing point.

30. In a typewriting machine, the combination of two platens, a printing point cover connected to one of said platens, and line spacing devices operative to advance the other platen in line spacing direction, certain actuations only of said devices operating to render said cover ineffective.

31. In a typewriting machine, the combination of a platen, a shield covering the printing point and connected to said platen, a rotary paper carrier, and means operative to move said platen, also to cause said shield to uncover the printing point, and also to actuate said carrier.

32. In a typewriting machine, the combination of types, a platen, a shield covering

- the printing point thereon, a rotary paper carrier, and means for moving said shield out of the path of the types and for turning said carrier.
- 5 33. In a typewriting machine, the combination of two rotary platens, hand actuated means for communicating opposite rotary movements to said platens, a rotary paper carrier, and connections between said paper carrier and one of said platens. 70
34. In a typewriting machine, the combination of two rotary platens, line spacing devices for rotating one of said platens at each actuation, and a rotary paper carrier connected with the other platen, said line spacing devices operating intermittently to turn said other platen and said carrier in the opposite direction from the first named platen. 75
- 15 35. In a typewriting machine, the combination of a rotary platen, a second rotary platen coaxial therewith, a rotary paper carrier connected with said second platen, paper feeding devices co-operative with said first named platen, line spacing devices co-operative with said first named platen to advance paper thereover, and connections for enabling said line spacing devices to intermittently turn said second platen and said carrier in the opposite direction from the first named platen. 80
- 20 36. In a typewriting machine, the combination of two platens, hand actuated devices for moving said platens oppositely, and a roll holder connected with one of said platens and rotatable by said hand actuated devices. 85
- 25 37. In a typewriting machine, the combination of two platens, hand actuated devices for moving said platens oppositely, a roll holder connected with one of said platens and rotatable by said hand actuated devices, a polygonal head connected to one end of said holder, and a double detent spring co-operating with diametrically opposite sides of said head. 90
- 30 38. In a typewriting machine, the combination of two rotary platens, a shield normally covering the printing point on one of said platens and connected therewith, a rotary paper carrier connected to said last named platen, and hand actuated means for communicating rotary movements in opposite directions to said platens and for simultaneously moving said shield to uncover the printing point and turn said carrier. 95
- 35 39. In a typewriting machine, the combination of a platen, an inking ribbon, printing types, a shield in the path of the types, and hand actuated means for feeding the ribbon and moving the shield to inoperative position. 100
- 40 40. In a typewriting machine, the combination of a rotary platen, a shield secured thereto and providing with the platen a slot
- for the paper, printing types, said shield being normally in the path of the types, an inking ribbon, and means for communicating a rotary movement to the platen and moving the shield out of the path of the types and also for feeding the inking ribbon. 105
41. In a typewriting machine, the combination of a platen, paper feeding devices co-operative therewith, line spacing devices for said platen, a second platen, and an intermittently operative connection between the two platens, said connection operating at a predetermined point in the rotation of one of said platens. 110
42. In a typewriting machine, the combination of a platen, paper feeding devices co-operative therewith, line spacing devices for said platen, a second platen, and an intermittently operative connection between the two platens, said connection being rendered operative by said line spacing devices. 115
43. In a typewriting machine, the combination of a platen, paper feeding devices co-operative therewith, line spacing devices for said platen, a second platen, an intermittently operative connection between the two platens, said connection being rendered operative by said line spacing devices, and a severing device for the paper fed over said platens. 120
44. In a typewriting machine, the combination of a platen, paper feeding devices co-operative therewith, line spacing devices for said platen, a second platen, and an intermittently operating connection between the two platens, said connection operating to communicate a rotary movement to said second platen at least once during each complete rotation of the first named platen. 125
45. In a typewriting machine, the combination of a platen, a second platen coaxial therewith, a pair of gears having connections to said first named platen, and intermittent connections comprising a pawl and ratchet between said gears and said second platen. 130
46. In a typewriting machine, the combination of a platen, a second platen coaxial therewith, a gear connected to said first named platen, a second gear intermeshing with said first named gear, a shaft on which said second gear is loosely mounted, pawl and ratchet mechanism adapted to connect said shaft with said second gear, and constant connections between said shaft and said second platen. 135
47. In a typewriting machine, the combination of a platen, a second platen coaxial therewith, a gear connected to said first named platen, a second gear intermeshing with said first named gear, a shaft on which said second gear is loosely mounted, pawl and ratchet mechanism adapted to connect said shaft with said second gear, constant connections between said shaft and said sec- 140

ond platen, types, and a type shield coöperative with said second platen and normally in the path of the types.

48. In a typewriting machine, the combination of a platen, a second platen coaxial therewith, a gear connected to said first named platen, a second gear intermeshing with said first named gear, a shaft on which said second gear is movably mounted, pawl and ratchet mechanism adapted to connect said shaft with said second gear, a crank arm on said shaft, and a link connecting said crank arm with said second platen.

49. In a typewriting machine, the combination of a platen, a second platen, connecting devices, and means operative automatically by the rotation of one of said platens to render said connecting devices intermittently operative and inoperative.

50. In a typewriting machine, the combination of a platen, a second platen, connecting devices, means operative automatically by the rotation of one of said platens to render said connecting devices intermittently operative and inoperative, and a severing device for cutting the paper fed over said platens.

51. In a typewriting machine, the combination of a platen, a second platen, connecting devices comprising pawl and ratchet mechanism, and means rendered operative automatically by the rotation of one of said platens to render said pawl intermittently operative and inoperative on said ratchet.

52. In a typewriting machine, the combination of a platen, a second platen, connecting devices comprising pawl and ratchet mechanism, and a fixed cam rendered operative by the rotation of one of said platens on said pawl to throw it into and out of said ratchet.

53. In a typewriting machine, the combination of a platen, a second platen coaxial therewith, a pair of gears having connections to said first named platen, a pawl on one of said gears, a coöperating ratchet connected to said second platen, and a cam for throwing said pawl into and out of mesh with said ratchet.

54. In a typewriting machine, the combination of a platen, a second platen, a gear secured to said first named platen, a second gear intermeshing with said first recited gear, a shaft on which said second gear is loosely mounted, a paper carrier rotatable on said shaft, connections between said shaft and said second platen, a ratchet wheel on said paper carrier, a second ratchet wheel on said shaft, a pawl on said second gear, and means for automatically affording a connection between said pawl and said ratchet wheels.

55. In a typewriting machine, the combination of a platen, a second platen, a gear secured to said first named platen, a second

gear intermeshing with said first recited gear, a shaft on which said second gear is loosely mounted, a paper carrier rotatable on said shaft, connections between said shaft and said second platen, a ratchet wheel on said paper carrier, a second ratchet wheel on said shaft, a pawl on said second gear, a spring normally tending to press said pawl into engagement with said ratchet wheels, and a cam operative to disengage said pawl from said ratchet wheels.

56. In a typewriting machine, the combination of a rotary platen, a platen axle, line spacing devices for said platen, a pair of ribbon spools on said platen axle and arranged at one end of the platen, guiding devices for guiding the ribbon in a plurality of folds lengthwise of said platen and from one spool to the other, and means for connecting and disconnecting said spools in alternation with and from said platen axle.

57. In a typewriting machine, the combination of a platen carrier, a platen thereon, ribbon spools on said platen carrier arranged side by side, projections on the inner faces of said ribbon spools, a settable engaging device adapted to be swung into alternate engagement with the projections on the two ribbon spools, and a friction spring on said device and engageable in alternation with the ribbon spools.

58. In a typewriting machine, the combination of a rotary platen, a pair of ribbon spools arranged side by side at one end of the platen and coaxial therewith, means for guiding the ribbon from one spool to the other lengthwise of the platen and from end to end thereof, and means for at will alternately connecting the ribbon spools to turn with the platen.

59. In a typewriting machine, the combination of a rotary platen provided with an axle, a pair of ribbon spools arranged side by side at one end of the platen and coaxial therewith, means for guiding the ribbon from one spool to the other lengthwise of the platen and from end to end thereof, and a lever pivoted to said axle between said spools and alternately engageable with said spools to connect them with said axle.

60. In a typewriting machine, the combination of a rotary platen, a pair of ribbon spools arranged side by side at one end of the platen and coaxial therewith, turning devices forward of said spools for guiding the ribbon from said spools inward longitudinally of the platen, and guiding devices at the opposite end of the platen for the ribbon, the ribbon overlying the printing face of the platen in a plurality of plies or folds.

61. In a typewriting machine, the combination of a rotary platen, line spacing devices therefor, a pair of ribbon spools arranged side by side at one end of the platen and coaxial therewith, turning devices for

ward of said spools for guiding the ribbon from said spools inward longitudinally of the platen, guiding devices at the opposite end of the platen for the ribbon, the ribbon 5 overlying the printing face of the platen in a plurality of plies or folds, and connections between said line spacing devices and said ribbon spools, said connections operating to alternately connect said ribbon spools with 10 said line spacing devices.

62. In a typewriting machine, the combination of a slidable platen carriage, a divided platen thereon, a slidable support back of said carriage, connections between said 15 support and said carriage, roll holders on said support, the paper from one of said roll holders being narrow and coöperating with one section only of said platen, the paper from the other roll holders being wider and 20 coöperating with both sections of the platen, a receiving roll holder for the narrow sheet mounted on the platen carriage, paper feeding devices coöperative with one of said platen sections, and means for actuating said 25 paper feeding devices and turning said receiving roll holder.

63. In a typewriting machine, the combination of types, a platen, a type shield, a 30 spring constantly tending to maintain said shield in the path of the types, means for moving said shield out of the path of the types against said spring, and devices for rendering said means ineffective and permitting said spring to restore said shield to 35 normal position in the path of the types.

64. In a typewriting machine, the combination of types, two platens, hand actuated devices for moving said platens oppositely, a type shield movable with one of said platens, 40 and automatic means for restoring said type shield to normal position together with the platen with which said type shield is movable.

65. In a typewriting machine, the combination of types, two platens, hand controlled means for communicating opposite rotary movements to said platens, a type shield mounted on one of said platens, and 45 spring means for restoring said type shield and its platen to their first or original position after they have been actuated by said hand controlled means.

66. In a typewriting machine, the combination of types, a platen, a type shield 55 mounted on the platen and normally in the path of the types, the paper passing around the platen between it and the type shield, means for moving the type shield out of the path of the types and for simultaneously advancing the work sheet over the platen in printing direction.

67. In a typewriting machine, the combination of types, a platen, a type shield mounted on the platen and normally in the 60 path of the types, the paper passing around

the platen between it and the type shield, means for advancing the work sheet in line space direction and for simultaneously moving the type shield in the opposite direction out of the path of the types.

68. In a typewriting machine, the combination of types, a platen, a type shield fixed thereto and normally in the path of the types, means for communicating rotary movement to the platen and carrying said 75 type shield out of the path of the types and for simultaneously advancing a work sheet which passes between the platen and the shield, and spring means for restoring said shield to normal position.

69. In a typewriting machine, the combination of types, a platen, a type shield fixed thereto, and normally in the path of the types, means for communicating rotary movement to the platen and carrying said 80 type shield out of the path of the types and for simultaneously advancing a work sheet which passes between the platen and the shield, and spring means for restoring said shield to normal position, said spring means 85 constantly tending to turn the shield forward or in the direction in which the paper is advanced for line spacing.

70. In a typewriting machine, the combination of types, a platen, a type shield fixed 95 thereto and normally in the path of the types, a paper receiving roll holder on which is wound a work sheet that passes between the platen and the shield, means for communicating rotary movement to the platen 100 and carrying said type shield out of the path of the types and for simultaneously turning said roll holder to advance the work sheet through a line space distance, and spring means for restoring said shield to normal 105 position.

71. In a typewriting machine, the combination of types, a platen, means for feeding a plurality of work sheets over said platen, transfer media being interleaved with said 110 work sheets, means for preventing coöperation of the types with certain only of said work sheets when the types are actuated, and means for withdrawing said preventive means from operation.

72. In a typewriting machine, the combination of types, a platen, means for feeding a plurality of work sheets over said platen, transfer media being interleaved with said 115 work sheets, a shield interposed between the platen and the innermost of said work sheets and normally preventing the type impressions from registering on said innermost work sheet, and means for withdrawing said shield so that the types may print simultaneously on all of said work sheets.

73. In a typewriting machine, the combination of types, a divided platen, means coöperative with one section of said platen for feeding a plurality of wide work sheets over 120

both sections of said platen, independent means for feeding a narrow sheet over the other section only of said platen, transfer media being interleaved with said work sheets, a shield normally interposed between the types and said narrow sheet so that the type impressions will be made on said wide sheets only, and means for withdrawing said shield so that the type impressions will be made simultaneously on all of the work sheets.

74. In a typewriting machine, the combination of types, a divided platen, means coöperative with one section of said platen for feeding a plurality of wide work sheets over both sections of said platen, independent means for feeding a narrow sheet over the other section only of said platen, transfer media being interleaved with said work sheets, a shield normally interposed between the types and said narrow sheet so that the type impressions will be made on said wide sheets only, and means for withdrawing said shield so that the type impressions will be made simultaneously on all of the work sheets, said last recited means operating at the same time to advance said narrow sheet in line spacing direction.

75. In a typewriting machine, the combination of types, a divided platen, means coöperative with one section of said platen for feeding a plurality of wide work sheets over both sections of said platen, and independent means for feeding a narrow sheet over the other or second section only of said platen, transfer media being interleaved with said work sheets, a shield extending lengthwise of the second section of said platen and secured to said second section near the ends thereof, a narrow sheet passing between said shield and said second section, said shield normally interposed between the types and said narrow sheet, and means for turning said second section slightly and withdrawing said shield from the path of the types so that all the work sheets may be printed on simultaneously.

Signed at the borough of Manhattan, city of New York, in the county of New York, and State of New York, this 9th day of October A. D. 1912.

ARTHUR W. SMITH.
